[57] CLAIM

The ornamental design for a mercury removing device for dental amalgamators, as shown and described.

DESCRIPTION

FIG. 1 is a perspective view of a mercury-removing device for dental amalgamators showing my new design;

FIG. 2 is a front elevation thereof;

FIG. 3 is a rear elevation thereof;

FIG. 4 is a top plan view thereof; and

FIG. 5 is a cross-sectional view taken on the line 5—5 of

FIG. 4;
